UNITED STATES PATENT OFFICE.

PIERRE JOSEPH KAMPERDYK, OF NEW YORK, N. Y.

ELECTRIC BATTERY.

SPECIFICATION forming part of Letters Patent No. 763,674, dated June 28, 1904.

Application filed October 14, 1903. Serial No. 177,020. (No model.)

To all whom it may concern:

Be it known that I, PIERRE JOSEPH KAMPERDYK, a subject of the King of Belgium, residing in the city of New York, borough of Manhattan, in the county and State of New York, have invented a certain new and useful Improvement in Electric Batteries, of which the following is a specification.

The invention relates to primary cells, and 10 more particularly to the construction of the carbon electrodes and their disposition relatively to the other parts of the cells.

The object of the invention is to provide a carbon electrode in which great superficial area 15 may be obtained with little resistance, thus offering a maximum depolarizing-surface while occupying comparatively little space and permitting the size of the cell to be reduced without correspondingly lessening the output.

20 The invention consists in certain novel arrangements of parts and details of construction by which the above objects are attained, to be hereinafter described.

25 The accompanying drawings form a part of this specification and show preferred forms of the invention.

Figure 1 is a plan view of a battery-cell equipped with what I consider the best form of my improved carbon electrode. Fig. 2 is 30 a corresponding transverse vertical section. Fig. 3 is an end view of a portion of one of the electrodes on a larger scale, and Fig. 4 is a corresponding side view. Fig. 5 is a horizontal section, on a still larger scale, showing a 35 detail of construction; and Fig. 6 is a corresponding vertical section. Fig. 7 is an end view similar to Fig. 3, but showing a modified form; and Fig. 8 is a corresponding section on the line 8-8 in the preceding figure. Fig. 9 is 40 a vertical transverse section showing another modification, and Fig. 10 is a similar view showing still another form.

Similar letters of reference indicate like parts in all the figures where they occur.

45 A is the containing vessel of rectangular form, and B B' B' are three porous cups, shown as open shells, having their lower ends closed by embedding them in a layer of suitable cement in the bottom of the vessel, but which 50 may be of the usual or any approved form

and of any suitable material. The outer cups are shown as having the side omitted next the adjacent wall of the vessel A, and all are held in position by distance-pieces B', placed between them, as shown, and provided with openings in which the negative-pole electrodes C, shown as two flat zinc plates, are received and held close to the walls of the cups, but out of contact therewith. The cups are supplied with a depolarizing liquid and the surrounding space contains the exciting liquid in which the zinc plates are immersed. A positive-pole electrode is presented to each face of each zinc plate, the central cup B containing two positive-pole electrodes and the cups B' B' each 65 containing one.

In all the prior forms of carbons known to me the resistance offered to the passage of the current from a given point in the mass to the pole or metallic conductor increases in proportion to the distance traversed and is due to the specific resistance of the material. The main object of the present invention is to lessen this resistance by so disposing a conductor relatively to the mass of carbon as to 70 reduce as far as practicable the distance to be traversed through the mass. This may be accomplished in several ways. Fine filings of incorrodible metal may be added to the carbon in the mass, or wires of any conducting 75 metal may be introduced and protected against corrosion by dipping the carbon thus constructed in melted paraffin, thus closing the pores and protecting the wires, or wires of incorrodible metal may be used, or wires of 80 copper or other good conducting metal covered with a plating of incorrodible metal may be employed, or a combination of two or more of the above methods may be used together.

Referring to Figs. 1 to 6, inclusive, D' D' 90 are copper wires coated, as at d, with an incorrodible metal, as platinum, inclosed in small masses of carbon D, (shown as balls perforated diametrically and strung like beads on the wires to form slender pencils.) The 95 wires are joined at the upper and lower ends to copper plates D² D³, which, with the points of attachment, are protected against corrosion by a deposition of lead or other incorrodible metal or by a coating of cement, preferably 100

having bitumen or gutta-percha as its base. The carbon electrodes rest on the layer A' of bitumen or other cement in the bottom of the vessel and stand as near as practicable to the 5 walls of the cups, so as to reduce as much as possible the distance between the carbons and zines and correspondingly lessen the internal resistance of the cell. The pencils thus formed are arranged in rows parallel with 10 each other and with the face of the zinc plate, and the several upper plates D² are connected together by the wires D⁴ D⁵ to form the positive pole of the cell. The balls D rest one upon the other and preferably fit snugly on 15 the wires to insure contact. Each pencil or series of balls is closely adjacent to the next in the same row and to its immediate neighbors in adjacent rows, but are held sufficiently separated to permit the depolarizing liquid to 20 circulate freely, the globular form allowing the beads or balls forming the pencils to be very nearly in contact and still offer open channels of sufficient area to permit the required circulation and reaction.

25 In Fig. 7 I have shown the series of balls as replaced by solid pencils D⁶, of carbon, formed on cores of wire similar to the wires D'. This form has certain advantages of strength and stability; but the pencils must 30 be placed relatively farther apart than the pencils of balls in order to insure the required space for circulation.

Fig. 9 shows a porous cup in which is placed sheets or plates D⁷ of incorrodible conducting 35 metal or of protected metal, the space between the sheets and between the latter and the walls of the cup being filled with balls or beads D⁸, and in Fig. 10 a framework of wires D⁹, of similar metal joined together, is placed 40 in a porous cup, which is then filled with carbon balls D¹⁰ or small masses of carbon. In both these forms of the invention a maximum of surface is secured; but the interstices through which the depolarizing liquid must 45 circulate are restricted. In these forms, and in the others, filings of incorrodible metal may be mixed with the carbon to increase the conductivity.

Although I have shown the beads as globular and prefer that form as giving the greatest surface with the least volume and the greatest attainable circulating-space, it will be understood that the beads may be cylindrical, spheroidal, or of other regular or irregular shapes.

The arrangement of containing vessel and porous cups is a preferable one, but is not essential to this invention. Any preferred forms of receptacles may be employed, and 55 their arrangement may be varied as desired.

I claim—

1. An electrode comprising a plurality of bead-like masses of carbon, and a metallic conductor proof against corrosion, inclosed in said masses. 65
2. An electrode comprising a plurality of perforated globular masses of carbon, and a conducting-wire proof against corrosion extending through the perforations in said masses and supporting the latter. 70
3. An electrode composed of pencils arranged close together, each of said pencils comprising a conducting-wire proof against corrosion, inclosed in carbon. 75
4. An electrode composed of pencils arranged close together, each of said pencils comprising a conducting-wire proof against corrosion, and a plurality of globular masses of carbon perforated and strung on said wire. 80
5. An electrode composed of carbon in a number of small masses, and an incorrodible conductor arranged to contact with such masses. 85
6. A positive-pole electrode composed of a plurality of parallel rows of carbon pencils, and a conducting-wire inclosed in each of said pencils and protected against corrosion, the said wires performing the double function of supporting the carbon and increasing the conductivity of the pencils, whereby a great number of pencils of small diameter may be mounted in a given space and the depolarizing-surface correspondingly increased. 90
7. A positive-pole electrode composed of a series of pencils of carbon arranged in rows, conducting-wires inclosed in said pencils and proof against corrosion, in combination with plates of conducting material protected against corrosion, to which the ends of said wires are attached. 95
8. In a primary battery, a containing vessel, one or more porous cups, and one or more flat plates of zinc serving as negative-pole electrodes, in combination with one or more positive-pole electrodes composed of pencils of carbon arranged in rows parallel with each other and with the plane of said plates. 100
9. An electrode comprising a wire of conducting metal having a coating of incorrodible material thereon, in combination with a series of globular masses of carbon perforated to receive said wire and strung thereon. 105

In testimony that I claim the invention above set forth I affix my signature in presence of two witnesses.

PIERRE JOSEPH KAMPERDYK.
